(57) **CLAIM**

The ornamental design for a foldable chair frame as shown and described.

DESCRIPTION

FIG. 1 is a front elevational view of a foldable chair frame showing the new design;

FIG. 2 is a rear elevational view thereof;

FIG. 3 is a left-side elevational view thereof;

FIG. 4 is a right-side elevational view thereof;

FIG. 5 is a top plan view thereof;

FIG. 6 is a bottom plan view thereof;

FIG. 7 is a first perspective view thereof;

FIG. 8 is a second perspective view thereof; and,

FIG. 9 is an enlarged view of the encircled portion '9' in FIG. 7 thereof.

The broken lines shown in the drawings are for the purpose of illustrating portions of the article, and boundaries of the enlarged view, and form no part of the claimed design.
